UNITED STATES PATENT OFFICE.

WILLIAM N. RETTINGER, OF BOURBON, INDIANA.

WASHING MACHINE.

Application filed January 25, 1922. Serial No. 531,705.

To all whom it may concern:

Be it known that I, WILLIAM N. RETTINGER, a citizen of the United States, residing at Bourbon, in the county of Marshall 5 and State of Indiana, have invented certain new and useful Improvements in Washing Machines, of which the following is a specification, reference being had therein to the accompanying drawings.

10 This invention relates to a washing machine, and the object of the invention is the construction of a simple and efficient machine for washing clothes, and the like.

Another object of the invention is the improvement of the construction of the stirrer device of a washing machine.

With these and other objects in view, my invention comprises certain novel combinations, constructions and arrangements of parts as will be hereinafter described, illustrated in the accompanying drawings, and more particularly pointed out in the appended claims.

In the drawings:

25 Figure 1 is a front view, in elevation, of a machine constructed in accordance with the present invention, showing the cover and stirrer device in an open position.

Figure 2 is a top plan view of my machine with the cover closed.

Figure 3 is a fragmentary, sectional view of the washing machine, showing the stirrer device in side elevation.

Figure 4 is a perspective view of the stirrer device.

The washing machine is provided with the usual receptacle 1 which is of a conventional construction and is to receive the water, clothes and a suitable soap or washing compound. This receptacle is provided 40 with a cover 2 which is hingedly mounted as shown at 3 for swinging movement from the open position of Figure 1 to the closed position of Figure 2 and a suitable latch 4 is provided so that the cover may be retained 45 in the closed position.

Extending through the top of cover 2 is the shaft 5 of the stirrer device. Shaft 5 is secured, at its inner end, to head 7, which 50 head is bifurcated, at 8, and straddles the board 9. Straddling the board 9, and flared out at their lower ends are wings 10; these wings 10 are substantially V-shaped and are provided for agitating or stirring the water in receptacle 1 and forming a good body of suds. Fingers 11 are fastened, at their inner

ends, to board 9 and extend downwardly therefrom between the flaring wings 10 and in diverging relation in the direction of the ends of the board. These fingers 11 will 60 engage the clothes and will cause them to be moved through the soapy water when the shaft 5 is rotated, the direction of movement being controlled by the direction in which the shaft is rotated. By having the 65 fingers positioned between the flaring wings the clothes will be moved in a path where the water is subjected to the greatest amount of agitation by the wings and this will cause the stirred up water to be passed 70 through the clothes in a very effective manner and the clothes thoroughly and quickly cleaned.

In order to mount the shaft for rotary movement, the upper end portion of this 75 shaft has been extended above the bearing head 12 which carries the cover lifting handle 13. Upon the extended end of the shaft there has been mounted a crank arm 14 pivotally and releasably engaged with a 80 pitman 15, so that as the pitman is reciprocated the shaft will be rotated first in one direction and then in the other. This pitman is pivotally connected with the crank arm 16 carried by the shaft 17 which is 85 journaled in the bearing 18 and it will be readily seen that when the shaft 17 is rotating oscillatory movement will be imparted to the shaft 5 to swing the stirrer first in one direction and then in the opposite direction. 90 In order to rotate the shaft 17 there has been provided a driving shaft 19 rotatably mounted and having at its outer end a pulley so engaged by a belt 21 and at its inner end a gear 22 which may be moved 95 into and out of engagement with a gear 23 by gear shifting means indicated in general by the numeral 24.

When this washer is in use the water, washing soap or compound and clothes will 100 be placed within the receptacle. The cover will then be closed and the pitman connected with the crank arm 14 and a suitable motor engaging the belt 21 will be started so that the shafts 19 and 17 will be rotated and 105 oscillating movement imparted to the stirrer. When the stirrer is in motion the wings will keep the water well agitated and the fingers will engage the clothes and cause them to be moved through the water and 110 thoroughly cleaned.

After the clothes are cleaned the pitman

will be disconnected from the arm 14 and swung to one side where it will be out of the way and the cover and stirrer can then be swung upwardly to the position of Figure 1.

5 The clothes can then be removed from the receptacle.

While I have described the preferred embodiment of my invention, and have illustrated the same in the accompanying drawings, certain minor changes or alterations may appear to one skilled in the art of which this invention relates, during the extensive manufacture of the same and I, therefore, reserve the right to make such alterations or changes as shall fairly fall within the scope of the appended claims.

What I claim is:

1. In a machine of the class described, the combination with a receptacle, and a cover 20 on said receptacle, of a stirrer device rotatably mounted on said cover, said stirrer device comprising a board, fingers depending from said board adjacent its ends, V-shaped wings straddling the end portions of 25 said board and extending upon opposite sides of said fingers, a head straddling said board intermediate said wings, a shaft secured to said head and extending through said cover, and means connected to said 30 shaft for rotating said stirrer device upon said cover.

2. In a machine of the class described, the combination with a frame, a receptacle carried by said frame, a cover on said receptacle, of a stirrer device rotatably mounted 35 on said cover, said stirrer device comprising a board, fingers depending from said board, wings projecting from opposite sides of said board, a head fastened to said board, a shaft secured to said head and extending 40 through said cover, and means connected to said shaft for rotating said stirrer device upon said cover.

3. In a machine of the class described, a receptacle, a cover for said receptacle, and a stirring device carried by said cover, said stirring device comprising a rotatable shaft journaled in said cover, a head board connected with and extending transversely of the shaft upon opposite sides thereof, flat 50 water agitating wings carried by the end portions of said head board and extending downwardly from opposite sides thereof in diverging relation, and clothes engaging fingers extending downwardly from the end portions of the head board between said wings and inclined in the direction of the free ends of the head board and means for imparting rotary movement to said shaft.

In testimony whereof I hereunto affix my 60 signature.

WILLIAM N. RETTINGER.
